UNITED STATES PATENT OFFICE

LAFAYETTE HOLT, OF BURLINGTON, NORTH CAROLINA

BEAM FOR SUPPORTING YARN PACKAGES

Application filed October 29, 1929. Serial No. 403,273.

This invention relates to an apparatus for simultaneously processing a plurality of independent yarn packages, each of which comprises a hollow perforated core on which is wound a quantity of yarn.

The object of the invention is to provide a support for a large number of such yarn packages and to construct the support in such a manner that the assemblage may be placed in a suitable processing machine or removed therefrom as a unit.

There are two types of processing machines in general use for treating yarn in bulk which is wound on a suitable beam.

One of these common types of machine is known as the vertical machine, and is adapted to receive the beam and to support the same in a vertical position within a suitable tank or vat, the processing fluid being passed into or circulated through the center or barrel of the beam, which is perforated, and outwardly through the bulk of yarn wound on the barrel.

The second type of processing machine is known as the horizontal type machine, and is adapted to receive and support a beam in a horizontal position within a suitable tank or vat, the processing fluid passing into the central perforated barrel of the beam and outwardly through the bulk of yarn wound thereon in the same general manner as in the vertical type machine.

In some instances the circulation of the processing fluid is reversed, that is to say the beam is submerged within the fluid and the fluid is drawn inwardly through the bulk of yarn through the perforated barrel and out one end thereof and returned to the vat or tank within which the beam is supported.

In some instances, especially in the horizontal type machine, the beam is adapted to be rotated at the same time as the fluid is being circulated through the beam and the bulk of yarn thereon in order to more evenly distribute the fluid through the bulk of yarn. This is especially desirable in dyeing and bleaching.

In the beams above described the fluid enters or leaves the barrels of the beam through one end thereof only, consequently the yarn

at the fluid-receiving or discharging end of the beam has been shown in practice to have been processed to a greater extent than the yarn at the distant end of the beam.

The yarn package support forming the subject of the present invention in general appearance resembles the beams above noted, differing therefrom in that a number or series of yarn packages are axially aligned with each other on a suitable carrier and a number of these loaded carriers are supported in and between a pair of laterally spaced heads corresponding to the end flanges of the bulk yarn beams, these heads being held in rigid axial alignment with each other for supporting the yarn packages therebetween.

The loaded supporting beam forming the subject of this invention is adapted to be placed in either of the types of processing machines above noted and in the same general manner as the bulk yarn beams.

The principal object of the present invention is to provide the supporting beam with means for directing the processing fluid into or out of both ends of each aligned series of yarn packages at one and the same time, the fluid flowing in opposite directions through each series toward the center of the series and at the same time passing radially through the perforated core members of the individual yarn packages and through the quantity of yarn wound thereon.

Obviously the direction of flow may be reversed or it may alternate in the same general manner as practiced with the bulk yarn beams, the main point of the present invention being that regardless of the direction in which the fluid may be flowing in the machine the said fluid will be flowing in opposite directions at the same time through each series of yarn packages carried by the supporting beam.

The construction and operation of the device will be more fully disclosed hereinafter, reference being had to the accompanying drawings, of which:

Fig. 1 is a longitudinal sectional elevation of my improved supporting beam taken on the line 1-1 of Fig. 2; and

100

Fig. 2 is a transverse sectional elevation taken on the line 2—2, Fig. 1.

In the present instance, my improved supporting beam comprises a pair of hollow heads 1 and 2 respectively, which, in the present instance, are circular in form and are supported in lateral spaced relation with respect to each other on a shaft 3 which is axially aligned with the heads 1 and 2.

10 The head 1 comprises a circular disk or plate 5 having a hub 6 adapted to receive the shaft 3, the said hub being held against axial movement with respect to the shaft between a pair of threaded collars or nuts 7 and 8 respectively. Concentric with the axis of the shaft 3 the plate 5 is provided with an annular flange 9, radially extending ribs 10, 10 being provided between the hub 6 and the said flange 9.

20 Parallel to the plate 5 and spaced apart therefrom by a ring 11 is a second plate 12 between which and the plate 5 is provided a fluid space or chamber 13. The plate 12 is centrally apertured to receive the shaft 3 and 25 is held in rigid contact with the collar 7 by means of a second collar 14 and a nut 15, the latter of which is threaded on to the threaded portion 16 of the shaft 3.

The hollow head 2 comprises an outer 30 plate 25 and an inner plate 26 which is parallel to and spaced apart from the plate 25 by means of a ring 27 providing a fluid space 28 between the said plates. Both of said plates are centrally apertured to receive the threaded end 29 of the shaft 3, the plate 26 abutting against a collar 30 secured to the said shaft 3, a collar 31 being mounted on the said shaft at the opposite side of the plate 26 and forming the spacer between the plates 26 and 25 35 respectively. Positioned on the shaft 3 at the opposite side of the plate 25 is a collar 32 and outside the collar 32 is a nut 33 by which the elements of the head 2 are held in rigid relation to each other on the shaft 3.

40 Adjacent the outer peripheral edge of each of the heads 1 and 2 is a series of bolts or screws 34 which pass through the parallel plates of which the respective heads are formed and the spacing rings interposed between the said plates.

The plates 12 and 26 of the heads 1 and 2 respectively are provided with circular openings 35, 35 disposed in axial alignment with respect to each other and adapted to receive the respective ends of the carriers 36 on which the individual yarn packages are supported.

45 As shown in Figs. 1 and 2, the carriers 36 are hollow and are rectangular in cross section and are adapted to extend between the heads 1 and 2 and into the hollow spaces 13 and 28 of the heads 1 and 2 respectively, the diameter of each of the openings 35 in the said heads being substantially equal to the measurement across the corners of the said 50 rectangular carriers 36, whereby the carriers

are held against lateral movement with respect to the said heads but space is provided between the flat walls of the carriers and the circular walls of the supporting openings to permit a flow of fluid through the said circular openings as will be more fully described hereinafter. The carriers 36 are perforated as indicated at 38 for purposes hereinafter described.

55 As shown in Fig. 1 of the drawings, each of the individual yarn packages α comprises a perforated tubular core member α^1 on which is wound a suitable quantity of yarn α^2 , the said yarn being wound on the perforated core member to a place substantially in a line with the planes of the ends of the said core members. The inside diameter of each of the perforated core members α^1 is, like the openings 35 in the plates 12 and 26 respectively, substantially equal to the measurement across the corners of the rectangular carrier 36 so that a number of yarn packages placed on the carrier will be in substantially axial alignment with respect to each other and when the opposite ends of the loaded carrier are placed 60 in the openings 35 in the heads 1 and 2 respectively the said yarn packages will be in axial alignment with said openings.

65 On the inner face of the plate 12 of the hollow head 1 is secured by riveting, bolting, or any suitable form of fastening means, an annular member 40 which is threaded to receive the correspondingly threaded end of a tube 41 which is in axial alignment with and surrounds the shaft 3, a jam nut 42 being provided to lock the threaded end of the tube 41 in fixed relation to the hollow head 1.

70 On the inner face of the plate 26 of the hollow head 2 is secured a similar plate 43 which is provided with an elongated annular flange or hub 44 which is adapted to receive the opposite end of the conduit 41, the elongated hub 44 providing for relative axial movement within predetermined limits between the head 2 and the conduit 41.

75 For the purpose of moving the heads 1 and 2 toward each other in order to bring the ends of the axially aligned core members α^1 of each series of yarn packages into abutting contact with each other and with the inner faces of the plates 12 and 26 of the heads 1 and 2 respectively, I provide a plurality of rods 45 having heads 46 located on the outer side of the plate 5 of the head 1, the rod extending through the plate 5, space 13 and 80 plate 12 of the head 1, thence across the space between the heads 1 and 2 and through openings formed in the inner plate 26, the space 28 and the outer plate 25 of the head 2, the said rods 45 being threaded at 47 to receive nuts 48 by which the said clamping movement is effected.

85 To prevent the collapse of the parallel walls of the heads 1 and 2 when the heads are being moved toward each other to clamp the 90

yarn packages therebetween spacing members 49, 49 are provided in the spaces 13 and 28 of the heads 1 and 2 respectively. The rods 45 passing through suitable openings formed in the spacing members 49. In order to maintain the spacing members in place at such times as the rods 45 may be entirely removed from the heads 1 and 2 bolts 50, 50 are provided which pass through the plates 10 of the respective heads and the spacing member therebetween.

The outer plate 5 of the head 1 intermediate the radial ribs 10 is provided with a number of openings 60 which afford communication to the interior of the hollow space 13 in the head 1. The inner plate 12 of the head 1 is provided with a number of openings 61 spaced around the shaft 3 and affording communication between the hollow space 13 of the head 1 and the interior of the conduit 41. The inner plate 26 of the head 2 is provided with a similar number of openings 62 which afford communication between the interior of the conduit 41 and the space 28 of the head 2.

As shown in Fig. 1, the shaft 3 is provided with plane bearing surfaces 65, 65 at its opposite ends which are adapted to be inserted in suitable bearings in the vat or tank of the processing machine (not shown).

In order to load the supporting beam the nuts 33 and 48 are backed off on the shaft 3 and rods 45 respectively, permitting the head 2 to be moved in a direction away from the head 1 a sufficient distance to accommodate the total length of the carriers 36, the hub 44 of the head 2 sliding on the conduit 41 during such movement.

A suitable number of the yarn packages α are placed on a number of the carriers 36 corresponding to the number of holes 35 in the heads 1 and 2, respectively. After the carriers are loaded in this manner one end of each carrier is positioned in one of the holes 35 in the head 1, the opposite end of the carrier being aligned with the corresponding opening 35 in the head 2. After the proper number of carriers are positioned in this manner the head 2 is moved toward the head 1, the nuts 33 and 48 being drawn down tightly to cause the ends of the perforated cores α^1 of the yarn packages α to be pressed against each other and against the inner faces of the plates 12 and 26 in tight abutting contact so that no fluid will be permitted to escape between the adjacent yarn packages or between the yarn packages and the supporting heads 1 and 2, thereby causing the fluid to pass through the yarn wound on the said core members. The beam having been loaded in the manner above described is then placed in the processing machine with the annular flange 9 in registry with a suitable fitting in the machine through which the fluid is adapted to pass from a suitable pump

by which the fluid is circulated in the machine.

In the vertical type machine this fitting is usually located in the bottom of the vat and the flange 9 rests in the fitting in such a manner that a seal is provided between the flange and the fitting. In the horizontal type machine this fitting is adapted to be clamped in any suitable way to the flange 9 to effect the desired seal therebetween and in cases where the beam is to be rotated, while circulation is taking place, the fitting with which the flange 9 co-operates is constructed in a manner to permit of the rotation of the flange 9 and still maintain an efficient seal between the fitting and the flange.

The fluid is adapted to pass through the opening 60 in the plate 5 into the chamber 13 in the head 1, filling said chamber and passing through the perforations 38 in the ends of the carriers 36 and through the openings 35 in the plate 12 into the core members α^1 of the yarn packages, the fluid flowing through the perforations 38 in the carriers 36 into the core members α^1 as well.

The fluid also passes from the chamber 13 in the head 1 through the opening 61 in the plate 12, thence through the conduit 41 and the opening 62 in the plate 26 of the head 2 into the chamber 38 in the head 2, the fluid filling the chamber 28 and passing into and through the carriers 36 and through the openings 35 of the plate 26 into the core members α^1 of the yarn packages.

In the manner above noted the fluid is being passed in opposite directions from each of the heads toward the center of the beam and at the same time flowing radially from the perforated core members α^1 through the yarn α^2 wound thereon. The fluid flowing out of the packages is collected by the tank or vat of the machine in which the beam is located and returned to the pump for circulation through the beam in the manner above noted for recirculation through the beam.

Circulation of the fluid in opposite directions through each series of aligned yarn packages effects a uniform processing of each and every one of the yarn packages contained in the series and eliminates the irregular processing above referred to.

In order to permit a free flowing of the fluid through the yarn packages, it is desirable to wind the yarn packages in what is known in the trade as open cross winding, that is each layer of thread is wound in spiral convolutions on the core member in one direction with the convolutions separated and the next layer is wound with the convolutions extending in the opposite direction and separated in the same manner as the first layer.

The plates 12 and 26 which come in actual contact with the yarn packages I prefer to make of a noncorrosive metal, for example "Monel" metal, and if desired in special cases

the entire beam may be made of like material which will not be affected by the processing fluid and which will not have an injurious effect upon any portions of the yarn packages 5 coming in contact with the elements of the beam.

In the drawings I have shown each head as having a series of carrier-receiving holes 35 spaced on an outer circle concentric with the 10 axis of the shaft 3 and a second series of holes spaced on an inner circle concentric with the outer circle, the outer circle having sixteen holes and the inner circle having eight holes, providing for the support of twenty-four carriers in all. In practice I have found that each carrier can readily support nine packages, making the total number of packages to be processed in one batch, two hundred and sixteen. Each package normally 20 is about six inches long and about five inches in diameter. Obviously, these dimensions may vary to suit requirements and the number of packages may be varied as desired, depending upon the number of packages in each 25 aligned series and the number of series employed. Obviously each carrier may support one or more packages depending upon the length of the package, and the number of carriers may be varied in accordance with 30 the diameter of the packages.

I claim:

1. In an apparatus for simultaneously processing a plurality of independent yarn packages, each of which comprises a perforated hollow core member on which a quantity of yarn is wound, the combination of a pair of laterally spaced hollow heads, a carrier extending between and into the hollow portions of said heads at its opposite ends, 25 said carrier having a plurality of said yarn packages thereon in end to end abutting contact relation to each other and provided with fluid passages permitting a flow of fluid from said hollow heads into the said perforated core members, and an imperforate duct connecting the hollow portions of said heads.

2. In an apparatus for simultaneously processing a plurality of independent yarn packages, each of which comprises a perforated hollow core member on which a quantity of yarn is wound, the combination of a pair of laterally spaced hollow heads, a carrier extending between and into the hollow portions of said heads at its opposite ends, 50 said carrier having a plurality of said yarn packages thereon in end to end abutting contact relation to each other and provided with fluid passages permitting a flow of fluid from said hollow heads into the said perforated core members, an imperforate duct connecting the hollow portions of said heads, and means for connecting the hollow portion of one of said heads to a source of fluid.

3. In an apparatus for simultaneously 55 processing a plurality of independent yarn

packages, each of which comprises a perforated hollow core member on which a quantity of yarn is wound, the combination of a pair of laterally spaced hollow heads, each head having a plurality of spaced openings 70 extending into the hollow portions thereof, a series of carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, an imperforate duct connecting the said hollow portions of said heads, and means for connecting the hollow portion of one of said heads to a source of fluid.

4. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings 75 extending into the hollow portions thereof, a series of carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, an imperforate duct connecting the said hollow portions of said heads, and means for connecting the hollow portion of one of said heads to a source of fluid.

5. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings 90 extending into the hollow portions thereof, and arranged on a circle concentric with the axis of said heads, a series of carriers extending between said heads with their respective opposite ends extending into the hollow portions of said heads through the said openings 95 therein, each carrier having a series of said yarn packages thereon in end to end relation to each other and provided with fluid passages permitting a flow of fluid from said hollow heads into the said perforated core members, an imperforate duct connecting the said hollow portions of said heads, and means for connecting the hollow portion of one of said heads to a source of fluid.

130

6. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings extending into the hollow portions thereof and arranged on a pair of circles concentric with the axis of said heads, a series of carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, to imperforate duct axially aligned with the axis of said heads and connecting the said hollow portions of said heads, and means for connecting the hollow portion of one of said heads to a source of fluid.

7. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings extending into the hollow portions thereof, a series of hollow perforated carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, an imperforate duct connecting the said hollow portions of said heads, and means for connecting the hollow portion of one of said heads to a source of fluid.

8. In an apparatus for simultaneously processing a plurality of independent yarn packages, each of which comprises a perforated hollow cylindrical core member on which a quantity of yarn is wound, the combination of a pair of laterally spaced hollow heads, each head having a plurality of spaced openings extending into the hollow portions thereof, a series of hollow perforated and flat sided carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members the inner cylindrical surface of each core member being engaged by the corners formed by the juncture of the flat sides of said carriers, an imperforate duct

connecting the said hollow portions of said heads, and means for connecting the hollow portion of one of said heads to a source of fluid.

9. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings extending into the hollow portions thereof and arranged on a circle concentric with the axis of said heads, a series of carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, an imperforate duct axially aligned with the axis of said heads and connecting the said hollow portions of said heads, means for connecting the hollow portion of one of said heads to a source of fluid, means for forcing the said heads toward each other to effect abutting contact between said core members and between the endmost core members and the respective heads, and a slip joint formed in said duct to permit of said relative movement between said heads.

10. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings extending into the hollow portions thereof and arranged on a circle concentric with the axis of said heads, a series of carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, an imperforate duct axially aligned with the axis of said heads and connecting the said hollow portions of said heads, means for connecting the hollow portion of one of said heads to a source of fluid, a shaft extending axially through said heads and said duct, and means on said shaft for forcing the said heads toward each other thereon.

11. In an apparatus for simultaneously processing a plurality of independent yarn packages, each of which comprises a perforated hollow core member on which a quantity of yarn is wound, the combination of a pair of laterally spaced hollow heads, each

- head having a plurality of spaced openings extending into the hollow portions thereof and arranged on a circle concentric with the axis of said heads, a series of carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, an imperforate duct axially aligned with the axis of said heads and connecting the said hollow portions of said heads, means for connecting the hollow portion of one of said heads to a source of fluid, a shaft extending axially through said heads and said duct, means in said shaft for forcing the said heads toward each other thereon, a series of rods spaced around the axis of said heads and extending parallel to the axis of said heads and between and through said heads to the outer sides thereof, and means on said rods for forcing the said heads toward each other to clamp the said yarn packages between said heads.
12. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings extending into the hollow portions thereof and arranged on a circle concentric with the axis of said heads, a series of carriers extending between said heads with their respective opposite ends extending into the hollow portions of said heads through the said openings therein, each carrier having a series of said yarn packages thereon in end to end relation to each other and provided with fluid passages permitting a flow of fluid from said hollow heads into the said perforated core members, an imperforate duct axially aligned with the axis of said heads and connecting the said hollow portions of said heads, means for connecting the hollow portion of one of said heads to a source of fluid, a shaft extending axially through said heads and said duct, means in said shaft for forcing the said heads toward each other thereon, a series of rods spaced around the axis of said heads and extending parallel to the axis of said heads and between and through said heads to the outer sides thereof, and means on said rods for forcing the said heads toward each other to clamp the said yarn packages between said heads.
13. In an apparatus for simultaneously processing a plurality of independent yarn packages, each of which comprises a perforated hollow core member on which a quantity of yarn is wound, the combination of a pair of laterally spaced hollow heads, each head having a plurality of spaced openings extending into the hollow portions thereof

LAFAYETTE HOLT.
